HARRY R. VAN DEVENTER AND ROBERT M. WARREN, OF NEW YORK, N. Y.; SAID WARREN ASSIGNOR TO SAID VAN DEVENTER, ASSIGNOR, BY MESNE ASSIGNMENTS, TO EXCEL PRODUCTS CORPORATION, A CORPORATION OF PENNSYLVANIA.

SWITCH BOX.

Application filed July 24, 1923. Serial No. 653,500.

Our invention relates to switches and particularly to switch boxes employed to control the energization of motor vehicle signal devices.

5 One object of our invention is to provide a relatively simple and compact structure for a switch box.

Another object of our invention is to provide a switch box that may be actuated by 10 the heel of an operator simultaneously with the actuation of a vehicle-controlling pedal.

Another object of our invention is to provide a switch box that shall have a depression in the cover member to constitute a heel 15 rest for the operator.

Another object of our invention is to provide a switch box that shall comprise a plurality of pairs of contact terminals for controlling or energizing signal devices to indicate intended movements of a motor vehicle with which the switch box is associated.

Another object of our invention is to provide a switch box having a cover that shall 25 constitute a heel rest for the operator in its normal neutral position and that shall be selectively tiltable to a plurality of operative positions.

Another object of our invention is to provide a switch adapted to be mounted adjacent to a vehicle-operating foot-pedal to be operated by the same foot as actuates the pedal and having an actuating member that is selectively tiltable to a plurality of positions corresponding respectively to different indications of intended movements of the vehicle with which it is associated.

Another object of our invention is to provide a switch box having a cover member 30 that is selectively tiltable in a lateral or in a longitudinal direction by the heel of an operator.

Another object of our invention is to provide a switch that shall be effective to actuate simultaneously a plurality of signal devices to indicate intended turning movements of a motor vehicle.

In practicing our invention we provide a 35 skeleton base of metal, of substantially rectangular form. Upon the base are mounted a plurality of pairs of co-operating contact

members suitably insulated therefrom. A metal cover member, having an integral and downwardly extending peripheral flange, is located above the skeleton base and is yieldingly pressed away therefrom by a single resilient member, means being provided to limit the extent of this movement. A thin plate of electric-insulating material is located 55 between the cover member and the contact member.

A plurality of longitudinally extending recesses are provided in the top surface of the cover member, the intermediate recess normally constituting a heel rest for the 60 operator. The outer recesses permit the operator to effect a turning or tilting movement of the cover member longitudinally of the base to effect engagement of certain of the contact members located at the side of 70 the switch box.

The cover member is further provided with an integral laterally upstanding flange, which may be engaged by the heel of the 75 operator to effect a turning movement of the cover laterally of the switch box, whereby certain other contact members are caused to engage each other.

In a modification of the device embodying our invention the cover member is provided 80 with a single, relatively deep, and longitudinally extending groove in its upper surface normally constituting a heel rest for the operator and permitting of the operator's effecting a tilting movement of the cover 85 member on a longitudinal axis, a front wall integral with the cover member permitting the operator to tilt the cover member on a lateral axis.

In the drawings, 90
Figure 1 is a view, in side elevation, of a motor vehicle with which is associated the device embodying our invention, a portion of the vehicle being cut away to show the location of the switch box. 95

Fig. 12 is a schematic diagram of connections employed with the device illustrated in 20 Figs. 2 to 6 inclusive, and

Fig. 13 is a schematic diagram of connections employed with the device illustrated in Figs. 7 and 8.

Referring more particularly to Figs. 2 to 25 6 inclusive a switch box aggregate 21 comprises a skeleton base 22 of metal. The base 22 comprises a peripheral flange that is substantially rectangular in outline and is provided at each side thereof with an integral lug 23 having an opening 24 therein to permit of mounting the base against a floor portion 25 of a motor vehicle 26 as illustrated more particularly in Fig. 1 of the drawing. An intermediate rib member 27 extends longitudinally of the base from the forward edge thereof to an intermediate and laterally extending relatively thin web 28 which is located near the rear end portion of the base 22.

40 Seat portions 29 are provided at three of the four corners of the base member 22 upon which are mounted stationary contact members 31 adjacent the rear edge of the base. Insulating members 32 are provided to insulate the contact members 31 from the metal base 22. A resilient two-part contact member 33 is insulatedly mounted on the base portion 22 adjacent the rear edge thereof by a suitable machine screw 34 which extends 45 through the middle portion of the member 33 and through an integral portion of the base member 22, and by a co-operating nut 35. An insulating member 32 is provided between the spring member 33 and the base portion 22. The two ends of the member 33 are normally out of engagement with the co-operating contact members 31 substantially as illustrated in Fig. 6 of the drawing.

At the forward edge of the base 22 a 50 single resilient contact member 36 has one of its ends insulatedly secured against the seat portion 29 located in the left forward corner of the base. Insulating washers 32 and 37 are employed to effectively prevent 55 any electrical contact between the contact

member 31 and the base 22. The free end of the member 36 extends to substantially the intermediate portion of the base laterally thereof and is so formed as to be normally disengaged from a co-operating stationary contact member 38 that is insulatedly mounted in the central web 27 on the base 22.

70 A cover member 39 is provided for the base portion 22 and comprises a top portion 41, an integral, depending, peripheral flange 42 and a laterally-extending upstanding flange portion 43. The cover member 41 is provided with a plurality of longitudinally extending depressions 44, 45, and 46, the 80 depressions 44 and 46 being located adjacent the side edges of the cover and the depression 45 being located intermediate thereof and extending across substantially the entire length of the cover member.

85 Means for yieldingly holding the cover member 39 away from the base portion 22 comprises a single spring member 47 that has one of its ends operatively engaging a depressed portion of the central web 27 substantially as illustrated in Fig. 3 of the drawing, and has its other end operatively engaging the under surface of the cover member 39. Integral lugs 48 may be provided in the upper surface of the depressed portion of the web 27 and the lower surface of the cover portion 41 in order to maintain the spring member 47 in its proper operative position and prevent any lateral movement thereof.

90 Means for limiting the movement of the cover member 39 away from the base 22 comprise a pair of relatively thin metal rods 49 that extend longitudinally of the switch box at each side of and closely adjacent to the central web 27 through openings 51 in the base portion 22 and through similar openings 52 in an integral, depending, and relatively short web 53 of the cover member 39. Openings 54 are provided in 100 the forward edge flange of the base 22 and in the integral web 28 through which the rods 49 extend. The openings 54 are larger than the lateral dimensions of the rods 49 and the amount of movement of the cover member 39 toward and away from the base 22 is limited by the size of the openings 54.

110 A thin sheet 55 of a suitable electric-insulating material is located between the lower surface of the cover member 39 and the top surfaces of the resilient contact members 33 and 36 in order that they may be operated by a suitable turning or tilting movement of the cover member relatively to the base member. The normal position 120 of the various parts comprising the assembled switch box is substantially as illustrated in Figs. 3, 5 and 6 of the drawings, that is, the cover member is yieldingly held at the maximum distance from the base more 130

particularly by the helical spring 47 but also, although to a lesser extent, by the action of the resilient contact members 33 and 36.

5 In Fig. 12 of the drawings I have illustrated schematically a diagram of connections employed with the switch box hereinbefore described in which a storage battery 56 is employed as a source of electromotive force and three signal lamps or devices 57, 58, and 59 are used. I have illustrated a grounded circuit for convenience only.

10 The switch box 21 is more particularly designed and constructed to be located on the floor 25 of a motor vehicle closely adjacent to an operating or vehicle-controlling foot pedal 61 that is adapted to be actuated by the foot of an operator in the usual well known manner.

15 20 In Figs. 7 and 8 there is illustrated a modified form of device embodying our invention differing mainly in the form of cover member provided for the base member 22. In this modification a cover member 62 is provided that is relatively deeper than the one illustrated in Figs. 2 to 6 inclusive, and that is provided with only a single, central, relatively deep and longitudinally-extending depression or groove 63. A plurality of integral and depending lugs 64 and 65 are provided that are respectively of such lengths as will bring their ends in substantially the same plane as that of the bottom surface of the groove portion 63. A sheet 55 of electric-insulating material is provided to suitably insulate the contact terminals from the cover member.

25 30 In this modified form of our invention we provide a two-part, resilient, bowed, contact member 33 adjacent the forward edge of the base portion that has its intermediate part insulatedly mounted on the forward end of the central web member 27. A plurality of stationary contact members 31 are insulatedly mounted at each forward corner portion of the base. A similar bowed contact member 33 is located adjacent the rear edge of the base as hereinbefore described.

35 40 The same resilient member 47 is provided to yieldingly hold the cover member away from the base and a plurality of rods 49 are employed as hereinbefore described to limit this movement.

45 50 Fig. 13 illustrates schematically a diagram of connections that is employed with this modified form of device embodying our invention, the operation of which will be more fully set forth hereinafter.

55 60 A signal box or device 66 is employed with the switch box hereinbefore described, and is intended to be mounted on a suitable part of the motor vehicle, preferably on the left rear fender thereof, substantially as illustrated in Fig. 1 of the drawings. This box

which is mounted a supporting plate 68 that is secured to the base plate by down-turned end portions 69 that may be suitably secured against upstanding lugs 71 integral with the base plate 67. The hereinbefore mentioned lamps 57, 58, and 59 may be mounted on the member 68 by being removably located in sockets 72 that are suitably secured on the supporting plate 68. If single contact lamps and sockets are employed the sockets 72 are electrically connected to the supporting plate 68 and therefore to the bottom plate 67, electric conductors 73, 74, and 75 being connected to the other contact of the lamp to permit of selectively controlling their energization by means of the hereinbefore described switch box.

70 75 A cover member 76 is provided for the base plate 67 and the lamps or signal devices mounted thereon, and this cover member 85 may be secured against the base plate 67 by a plurality of small machine screws 77. A plurality of spaced, depending, opaque diaphragms 78 are provided in the cover member 76 to which they may be secured by small machine screws 79, so located as to divide the space within the signal box 66 into three substantially equal compartments within which the lamps 57, 58, and 59 are located.

80 85 The front and rear walls of the cover member 76 are each provided with a plurality of perforations therethrough, the central perforation having the form of the letter S and the two side perforations having the form of an arrow. While any conventional form of the letter S and of the arrow may be employed, we prefer to make the form relatively simple and the perforations relatively narrow, substantially as illustrated in Figs. 9 and 10 of the drawing.

90 95 A plate 81 of multi-colored celluloid is provided adjacent the inside of the front and the rear walls of the cover member 76, that portion of the celluloid located within the intermediate chamber formed by the plurality of diaphragms 78 being colored red, while those portions located in the end parts of the cover member 76 are colored green. That is, when the lamp 58 is energized the letter S will be indicated in red, while if either lamp 57 or 59 is energized a green arrow is indicated.

100 105 If desired the construction of the cover member 76 may be slightly changed so as to provide a suitably colored background with the letter S and the arrows made translucent, whereby the letter S or an arrow will be caused to show or stand out against a red or a green background respectively.

110 115 Referring more particularly to the operation of the switch box described in Figs. 2 to 6 inclusive in connection with the diagram of connections illustrated in Fig. 12, the operator normally rests his heel with in the central depression 45 of the cover

120 125 130

member 39, the spring 47 being sufficiently strong to prevent the weight of the operator's foot from depressing or moving the cover member downwardly enough to cause any of 5 the co-operating movable and stationary contact members to engage each other.

The size of the openings 54 is such that no operative engagement of the respective contact members results when the cover 10 member is moved straight downwardly.

When the cover member is given a tilting or turning movement around a longitudinal axis, the downward travel of a lateral edge is, of course, much greater. The cover member turns around the opposite pin 49 and the movement of the other pin 49 in the slots 15 54 is magnified at the outer edge of the cover member, whereby operative engagement of the co-operating contact members is 20 assured. If the operator desires to turn the motor vehicle to the right and wishes to notify the operator of a following vehicle of this intended movement, he moves his heel into the right hand depression 44 of the 25 cover member 39 and by pressing downwardly thereon causes a tilting movement of the cover member on a longitudinal axis, thereby causing the right hand end of the resilient contact member 33 to engage its co-operating 30 stationary contact member 31, whereby the signal lamp 59 is energized and the right hand arrow in the signal box 66 is caused to be shown in green. This signal indicates to the operator of a following motor vehicle 35 that the vehicle in front of him intends to make a right hand turn.

In case the operator desires to make a left hand turn he places his heel in the depression 46, whereby a tilting movement of the 40 cover member is effected around a longitudinal axis, in the opposite or counter clockwise direction, and the left hand end of the bowed contact member 33 is caused to operatively engage its co-operating stationary contact 45 member 31, thereby energizing the lamp 57 and the left hand arrow in the signal box is caused to be shown in green.

If the operator of the motor vehicle desires to indicate to the operator of a following vehicle that he intends to stop, he causes 50 his heel to engage the upstanding flange 43 whereby the cover member is given a tilting movement around a lateral axis and the free end of the bowed contact member 36 is caused 55 to engage its co-operating stationary contact member. This energizes the intermediate lamp 58 whereby the letter **S** in red is caused to be shown in the signal box.

As hereinbefore noted, it is intended that 60 the switch box 21 be mounted closely adjacent to and at the rear of a vehicle-controlling foot-pedal, which may be either a clutch pedal or a brake pedal. If the operator actuates either the clutch or the brake pedal with 65 the usual forward movement, his heel will

automatically and simultaneously engage the flange 43, thereby causing the signal lamp 58 to be energized and display the letter **S** in red as hereinbefore described, thus giving warning of the intended movement of the 70 vehicle to the operator of a following vehicle. Should he desire to make a right hand or a left hand turn, he can easily simultaneously actuate the switch cover as hereinbefore described with the heel of his foot 75 without, in any way, hindering the operation of the foot pedal by the same foot.

It is easily seen that the hereinbefore described operation by the heel of the operator in causing a tilting movement of the cover 80 member around either a longitudinal or a lateral axis, is easily effected by reason of the provision of a single resilient member for yieldingly holding the cover member away from the base member, which resilient 85 member is placed in a substantially central position both longitudinally and laterally of the switch box.

In actually employing the switch box illustrated in Figs. 2 to 6 inclusive it was found possible to energize not only one of the signal lamps 57 or 59 by a tilting movement of the cover member around a longitudinal axis, but it was also found possible by a simultaneous forward tilting movement of 90 the cover member to energize the signal lamp 58, thereby making it possible to energize the intermediate signal device simultaneously with either one of the outer signal devices. This was taken advantage of in wiring the 95 switch box illustrated in Figs. 7 and 8 of the drawings and the diagram of connections to be employed therewith is illustrated schematically in Fig. 13 of the drawings.

The same tilting movement of the cover 100 member around a longitudinal axis is possible in this modified form of switch box as was hereinbefore described for the first form of switch box. However, a tilting movement of the cover member around a 110 longitudinal axis, say in a clockwise direction, energizes the signal devices 59 and 58, thereby illuminating two lamps and colored devices at the same time. This results in giving a more efficient signal to the operator 115 of a following vehicle than is given by only one signal device or signal indication. If a tilting movement of the cover member in a counter clockwise direction is effected, signal devices 57 and 58 are energized, while if the 120 cover member is given a tilting movement around a lateral axis only the intermediate signal device 58 is energized and the usual stop signal **S** is displayed.

As the cover member 63 is provided with 125 only a single longitudinally-extending and relatively deep recess therein the operator can easily effect a tilting movement thereof around a longitudinal axis without the necessity of moving his heel from one recess 130

or groove to another, in fact it is only necessary for him to turn his foot on the heel in the groove to the right or to the left in order to effect the desired tilting movement 5 of the cover member. When the switch box is located directly back of the clutch pedal lever a forward movement of the operator's foot, as necessitated by the operation of disconnecting the clutch, permits the operator's heel to engage the sloping front wall 10 of the recess and effect the desired forward tilting movement of the cover member as hereinbefore described.

It is of course obvious that any kind of 15 signal device may be controlled by the hereinbefore described devices and that for instance, an electro-magnetic device may be controlled instead of the lamps as hereinbefore described or one lamp and one electro- 20 magnetic device may be energized.

The device embodying our invention provides a relatively simple, compact, inexpensive, and easily operated means for selectively energizing one or more of a plurality 25 of signal devices that will indicate intended movements of the motor vehicle with which the switch box is operatively associated. Its operation may be effected without conscious effort on the part of the operator 30 after once having become accustomed thereto, thereby making its operation, in effect, an integral part of the normal operation of a motor vehicle.

Various modifications may be made in the 35 device embodying our invention without departing from the spirit and scope thereof, and such modifications are intended to be included in and covered by the appended claims.

40 We claim as our invention:—

1. A switch for a vehicle signal comprising a base, pairs of contact terminals for establishing circuits to indicate intended movements of the vehicle, and an actuating member mounted on the base and biased to a neutral position and selectively movable to a plurality of positions corresponding respectively to different indications of intended movements of the vehicle, the said actuating member being provided with a raised portion adapted to be engaged by the operator's heel when a pedal of the vehicle is depressed, so as to thereby move said member. 45

50 2. A switch for a vehicle signal comprising a base, pairs of contact terminals for establishing circuits to indicate intended movements of the vehicle, and an actuating member mounted on the base and biased to a neutral position and selectively movable to a plurality of positions corresponding respectively to different indications of intended movements of the vehicle, the said actuating member being provided upon its upper face with a central recess constituting

a rest for the operator's heel when the member is in a neutral position, and with a raised portion adapted to be engaged by the operator's heel when a pedal of the vehicle is depressed, so as to thereby move said member. 55

3. A switch for a vehicle signal comprising a flat base, co-operating pairs of contact terminals mounted on the base for establishing circuits to indicate intended movements 75 of the vehicle, a single actuating cover member mounted on the base, and a single spring interposed between the said member and the base for maintaining the former in neutral position. 80

4. A switch for a vehicle signal comprising a flat base, pairs of contact terminals for establishing circuits to indicate intended movements of the vehicle, an actuating cover member mounted on the base, and a 85 spring interposed between the said member and the base for maintaining the former in neutral position, the said actuating member being provided with a raised portion adapted to be engaged by the operator's heel when a pedal of the vehicle is depressed, so as to thereby move said member. 90

5. A switch for a vehicle signal comprising a flat base, pairs of contact terminals for establishing circuits to indicate intended 95 movements of the vehicle, an actuating cover member mounted on the base, and a compression spring interposed between the said member and the base for maintaining the former in neutral position, the said actuating member being provided upon its upper 100 face with a central recess constituting a rest for the operator's heel when the member is in neutral position, and with a raised portion adapted to be engaged by the operator's heel when a pedal of the vehicle is depressed, so as to thereby move said member. 105

6. A switch for a vehicle signal comprising a flat base, having integral means for permitting of securing said base on the floor 110 of a vehicle, co-operating pairs of contact terminals directly mounted on said base for establishing circuits to indicate intended movements of the vehicle, a single actuating cover member mounted on the base, and a single compression spring interposed between the said member and base and extending laterally to the respective faces thereof for normally maintaining the former in 115 neutral position. 120

7. A switch for a vehicle signal, comprising a base, co-operating pairs of contact terminals for establishing different circuits mounted on said base, and an actuating cover member mounted on the base, biased to neutral position and selectively tiltable laterally and longitudinally thereof to a plurality of positions corresponding respectively to different indications of intended movements of the vehicle. 125 130

8. A switch for a vehicle signal, comprising a base, an actuating cover member mounted thereon, interfitting therewith and biased to a neutral position and selectively 5 tilttable to a plurality of positions corresponding respectively to different indications of intended movements of the vehicle, and co-operating pairs of contact terminals mounted on said base corresponding respectively 10 to the several tilted positions of the actuating member.
9. A switch comprising a base member, a plurality of pairs of co-operating contact members insulatedly mounted on said base, 15 a cover member on said base member, a single means located between said base and said cover member for yieldingly holding said cover member a predetermined distance away from said base, and means integral 20 with said cover member for permitting movement thereof in a direction substantially at right angles to the face thereof to cause predetermined contact members to operatively engage each other.
10. A switch comprising a base member, a plurality of pairs of contact terminals mounted thereon, a cover member on said base, means for yieldingly holding said base and said cover member apart, and means 30 for limiting the separating movement of said members and for permitting a movement of said cover member in both a longitudinal and a lateral direction relatively to said base.
11. A switch comprising a base member, a plurality of co-operating pairs of terminals mounted thereon and controlling a plurality of signal devices, and a combined cover and terminal-actuating member 40 mounted on the base and tilttable relatively thereto, a lateral tilting movement causing the actuation of a plurality of signal devices and a longitudinal tilting movement causing the actuation of only one signal device.
12. A switch comprising a base member, a plurality of co-operating pairs of terminals mounted thereon for controlling the energization of a plurality of signal devices, and a combined cover and terminal-actuating member 50 mounted on the base and having integral means for permitting a tilting movement thereof by the heel of an operator in either a lateral or a longitudinal direction.
13. A switch comprising a base member, a plurality of co-operating pairs of terminals mounted thereon for controlling the energization of a plurality of signal devices, and a combined cover and terminal-actuat- 55
- ing member mounted on the base and having integral means for permitting a tilting movement thereof by the heel of an operator in either a lateral or a longitudinal direction, a lateral tilting movement causing the energization of a plurality of signal devices, and a longitudinal tilting movement causing the actuation of only one signal device. 60
14. Operation indicating mechanism for a vehicle having a control pedal and electrically controlled signal apparatus carried by the vehicle for indicating intended movements of the vehicle, comprising means for controlling said apparatus including switch mechanism mounted adjacent to the said pedal to permit of its actuation by pressure 70 exerted by the heel of the operator when actuating the pedal with his toe, and terminals and switch contacts the relative positions of which are such that when the actuating member is pressed centrally one circuit is 75 closed and when pressed on one side two circuits are closed.
15. Operation indicating mechanism for automobiles of the type having a foot operated control pedal comprising signaling means for indicating stops and turns, and means to effect operation of said signaling means mounted on a stationary part of said automobile adjacent to said pedal to permit of its actuation by pressure exerted by the heel of the operator when actuating the pedal with his toe, and comprising an operating part which when pressed centrally causes the said signaling means to indicate stopping of the automobile and which when 80 pressed laterally causes the signaling means to indicate turning of the automobile. 85
16. Operation indicating mechanism for automobiles of the type having a foot operated control pedal and comprising signaling means for indicating stops and turns, and means to effect operation of said signaling means mounted on a stationary part of said automobile adjacent to said pedal to permit of its actuation by pressure exerted by the heel of the operator when actuating the pedal with his toe, and comprising an operating part which when pressed centrally causes the said signaling means to indicate stopping of the automobile and which when 90 pressed laterally causes the signaling means to indicate turning of the automobile. 95
- In testimony whereof, we have hereunto subscribed our names this 20th day of July, 1923.
